UNITED STATES PATENT OFFICE.

JOHN LEE, OF CHESTER, PENNSYLVANIA.

PAPER-BAG HOLDER.

SPECIFICATION forming part of Letters Patent No. 416,845, dated December 10, 1889.

Application filed May 9, 1889. Serial No. 310,156. (No model.)

To all whom it may concern:

Be it known that I, JOHN LEE, a citizen of the United States, residing at Chester, in the county of Delaware and State of Pennsylvania, have invented certain new and useful Improvements in Paper-Bag Holders; and I do hereby declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 This invention relates to an improvement in paper and paper-bag holders, whereby a simple and inexpensive device is produced which is adapted for use as a paper or paper-bag holder or letter-file, as may be required.

20 The broad idea contained in this device is not novel, as many ways of carrying it out have been devised; hence my invention consists in the device herein described and claimed.

25 In the annexed drawings, Figure 1 is a side elevation of my invention as in use, representing one of a series of such devices. Fig. 2 is a right-hand elevation of the same.

The invention consists of two parts, A and 30 B.

A is a bale provided with an upturned hook 1 at its right-hand end, an eye 2 in its middle portion, and at its left-hand end a series of coils 3; forming a sheath or shield for the reception of the pointed end of wire pin B.

35 B is a wire pin pointed at one end and provided with an eye b at its opposite end.

To use my invention I string a number of bags or pieces of wrapping-paper C by piercing them through one corner or the middle part, as shown. Having secured a sufficient number on the pin B, I insert the pointed end of the pin in the shield 3 and pass the eye b of the pin over the free end of loop 1, as shown in Fig. 1.

40 My device may be suspended from a strip of wood D, provided with hooks d on its lower edge and eyebolts d'. From the latter are attached suspension wires or cords d², in the usual manner.

45 It will be seen from the above that my invention provides a cheap or inexpensive device of universal use in stores where various sizes of paper bags are used. The several sizes of paper or bags will be right before the

50 employé, available for use as required. There are no expensive frames or stands required, and there are no projecting sharp-pointed pins or hooks exposed by which the busy employé may be injured.

55 What I claim as my invention is—
A bale provided with a loop at one end thereof, an eye in its central portion, and a series of coils at its opposite end arranged in line with its hooked end, in combination with a pointed pin provided with an eye at its opposite end, as and for the purpose herein set forth.

60 In testimony whereof I affix my signature in presence of two witnesses.

JOHN LEE.
